UNITED STATES PATENT OFFICE.

MIKLOS CHUPKA, OF JOHNSTOWN, PENNSYLVANIA.

LIFE-BOAT AND LAUNCHING-DAVIT THEREFOR.

1,136,938.

Specification of Letters Patent.

Patented Apr. 27, 1915.

Application filed November 10, 1914. Serial No. 871,274.

To all whom it may concern:

Be it known that I, MIKLOS CHUPKA, subject of the Emperor of Austria-Hungary, residing at Johnstown, in the county of Cambria and State of Pennsylvania, have invented certain new and useful Improvements in Life-Boats and Launching-Davits Therefor, of which the following is a specification.

10 This invention relates to certain new and useful improvements in life boats and launching davits therefor.

The primary object of this invention is to provide closable life boats of water-tight construction with accommodating mounting brackets upon the gunwale portions of a vessel, the vessel being provided with a guard rail but allowing free launching of the boats.

20 A still further object is to provide railings along the gunwale portions of the deck of a vessel for forming open-sided inclosures adapted for the reception of life-boats mounted upon suitable brackets therein, 25 means being provided to allow the sailors to enter the inclosure and means also being provided for each life-boat whereby the same may be elevated above the level of the deck and then projected outwardly over the 30 water and lowered onto the surface of the same when the life-boats are filled with passengers.

With these general objects in view and others that will appear as the nature of the 35 invention is better understood, the same consists in the novel combination and arrangement of parts to be hereinafter more fully described, illustrated in the accompanying drawings and set forth in the appended 40 claim.

In the drawings forming a part of this application and in which like-designating characters refer to corresponding parts throughout the several views, Figure 1 is a 45 side elevation of the forward portion of a vessel provided with the present invention. Fig. 2 is a top plan view thereof. Fig. 3 is an enlarged side view of the life-boat hoisting device. Fig. 4 is a front elevation of 50 the hoisting device partly shown in section. Fig. 5 is a side elevation of one of the life-boats. Fig. 6 is a front plan view thereof, and Fig. 7 is a transverse sectional view of the same.

55 Referring more in detail to the drawings the vessel 10 is herein illustrated having

the deck 11 thereof provided with a marginal railing 12 spaced off into a plurality of partial inclosures 13 upon the opposite gunwale portions of the deck. These inclosures 13 have one open or outer side 14 for allowing the life-boats 15 which are normally positioned within the inclosures 13 to be laterally swung over the side of the vessel for launching into the water. Each 60 inclosure has the railing thereof provided with a gate 16 for allowing the sailors to enter the inclosure without climbing over the railing. Each inclosure is provided with opposite brackets 17 which are of substantially triangular form in side elevation and have inwardly and upwardly inclined flanges 18 adapted to be received within the upwardly inclined end sockets 19 formed in the outer wall of the life-boat and whereby 70 the life-boats are mounted horizontally positioned upon the deck of the vessel within the said inclosure. 75

A hoisting device is provided upon the deck for each of the life-boats and consists 80 of an upright post 20 revolvably mounted upon a base 21 and having anti-friction ball-bearings 22 positioned between the posts and base. A shaft 23 is transversely journaled through the top of the post and intersects a rectangular opening 24 extending through the said post and at right-angles to the said shaft. Rollers 25 are also journaled in the opening 24 at the top and bottom of the opening 24 and a supporting 85 beam 26 is slidably mounted upon the rollers 25 and through the opening 24, the said beam being provided with a central longitudinal slot 27 adapted for the reception of the shaft 23 and a toothed wheel 28 carried 90 by the said shaft, which wheel is in constant mesh with a rack 29 at the top of the slot 27. 95

At the side of the post normally facing the deck, the shaft 23 has a fixed sprocket wheel 30 over which runs a sprocket chain 31 which chain also passes over a similar sprocket wheel 32 positioned near the bottom of the post and adapted to be operated by a turn crank 33. A pawl 34 is pivotally secured to the post 20 which is adapted for 100 ratcheting engagement with a pinion 35. It will be seen by this description, that by turning the crank 33, the beam 26 may be longitudinally shifted through the post opening 24.

110 The life-boats 15 are each provided with cables 36 rigidly secured thereto for posi-

tioning a ring 37 centrally of the top of the boat and whereby the boat may be elevated by means of the hoisting device upon the deck of the vessel. A cable 38 is provided at 5 one end with a hook 39 adapted to engage the life-boat ring 37 while said cable passes over the pulley 40 which is mounted upon one end of the beam 26 by means of a bracket 41. A winding drum 42 is mounted upon the post 20, being operable by a turn crank 43 and the cable 38 has one end thereof secured to and wound upon the said drum. The drum 42 has a pinion 44 secured thereto while a pawl 45 carried by the post is adapted 10 to engage the teeth of this pinion.

From the present detailed description of the entire device it will be seen that with the life-boat 15 mounted upon the brackets 17 and with the cable hook 39 engaging the 15 boat ring 37, the crank 43 may be turned for slightly elevating the life-boat and whereupon the boat may be pushed outwardly over the side of the vessel and by turning the crank 33 in the proper direction, the beam 26 and the boat suspended therefrom will be projected outwardly away from the vessel simultaneously with a further elevation of the boat, it being understood that the post 20 is also revolved simultaneously. The elevating and projecting outwardly of the boat may also be accomplished by the mere turning of the crank 33 to outwardly position the beam 26, the post 20 being simultaneously revolved. The drum 42 may 20 then be released for unwinding the cable 38 and allowing the boat 15 to drop or be lowered onto the surface of the water.

It will be noted that the form of life-boat herein illustrated is provided with an end hatch 46 at the stern portion of the boat 40 which is entirely inclosed while windows 47 are provided at the stern of the boat and upwardly-projecting air tubes 48 are positioned through the deck thereof. A serviceable arrangement of safely-constructed life-boats 45 is thus provided upon the deck of the vessel arranged completely guarded at the opposite sides of the deck while serviceable launching means are provided for each boat.

While the forms of the invention herein 50 shown and described are what are believed to be the preferred embodiments thereof, it is nevertheless to be understood that minor changes may be made without departing from the spirit and scope of the invention as 55 set forth in the claim.

What I claim as new is:—

A device of the class described comprising in combination with the deck of a vessel, a railing arranged adjacent the gunwale 60 portion thereof and formed into spaced inclosures having open outer sides, and with hinged sections at their inner sides, life-boat mounting brackets substantially triangular in side elevation and having upwardly and 65 inwardly projecting flanges and oppositely mounted upon the railing at the ends of said inclosure for supporting a life boat.

In testimony whereof I affix my signature in presence of two witnesses.

MIKLOS CHUPKA.

Witnesses:

ALEX COVER,
JAS. A. FINLOW.
